AU 292 EX
OR D 20,067

DESIGN.

A. ROSENSTEIN.
CANE OR UMBRELLA HANDLE.

No. 20,067.

Patented July 29, 1890

UNITED STATES PATENT OFFICE.

ALBERT ROSENSTEIN, OF LANCASTER, PENNSYLVANIA.

DESIGN FOR A CANE OR UMBRELLA HANDLE.

SPECIFICATION forming part of Design No. 20,067, dated July 29, 1890.

Application filed June 26, 1890. Serial No. 356,721. Term of patent 3½ years.

To all whom it may concern:

Be it known that I, ALBERT ROSENSTEIN, of Lancaster, in the county of Lancaster and State of Pennsylvania, have invented certain new and useful Improvements in Designs for Cane, Umbrella, or Parasol Handles; and I do hereby declare the following to be a full, clear, and exact description of the invention, such as will enable others skilled in the art to 5
10 which it pertains to make and use it, reference being had to the accompanying drawing, which forms part of this specification.

My invention relates to an improvement in designs for cane, umbrella, or parasol handles; and it consists in an ornamental shape 15
15 which will be more fully described herein-after, and which imparts a novel and pleasing appearance to the handle.

The accompanying photographic illustration 20
20 represents my invention.

A represents the main portion of the handle, upon which are formed leaves of some plant, and from the upper end of which, at one side, is a slight projection B, as if a limb or portion had been cut away. Rising from the opposite upper corner of the trunk A is a limb or branch D, which is bent into a curved or hooked form, as shown, and around which a vine G is coiled. 25

Having thus described my invention, I 30
claim—

A design for cane, umbrella, or parasol handles, substantially as herein shown and described.

In testimony whereof I affix my signature in 35
presence of two witnesses.

ALBERT ROSENSTEIN.
